HARRY H. BELLMAN,
Inventor

By

Attorney

UNITED STATES PATENT OFFICE.

HARRY H. BELLMAN, OF READING, PENNSYLVANIA.

BOTTLE RECEPΤACLE.

Application filed May 9, 1921. Serial No. 467,829.

To all whom it may concern:

Be it known that I, HARRY H. BELLMAN, a citizen of the United States, residing at Reading, in the county of Berks and State 5 of Pennsylvania, have invented certain new and useful Improvements in Bottle Receptacles, of which the following is a specification.

This invention relates to improvements in 10 bottle containers and it pertains more particularly to a device intended for receiving and securely holding one or more milk bottles.

The invention is intended as a protective 15 device against theft of milk bottles delivered to the household, and it consists of a box like container, provided with a self locking cover, and means for securing the box in position at the door, so that the box 20 cannot be opened, nor can it be removed, without first opening the door by which it is held in position.

The invention is more fully described in 25 the following specification and clearly illustrated in the accompanying drawing, in which:—

Figure 1 is a vertical, central sectional 30 view of my container, showing two bottles in position, and with the cover locked in position thereon.

Figure 2 is a side elevational view thereof.

Figure 3 is a plan view, showing the container in position, held between the door and the door frame.

35 The numeral 1 designates the body of the container, which is preferably of rectangular form, and provided with a pair of horizontally disposed rods 2, which serve to hold the opposite walls of the box in shape, and 40 to form compartments for the bottles. The upper rod 2 also serves as a means of engagement for the cover locking device, described later.

The cover 3, is adapted to fit snugly over 45 the box or body 1, and it is provided with a handle 4.

To the under side of the box lid 3, is pivotally suspended a hook 5, the free curved end of which will automatically fall beneath 50 the upper rod 2 when the lid or cover is placed in position, as shown in Figure 1. This engagement of the hook with the rod 2 will effectively lock the cover, and prevent

the removal thereof until it is released by slightly tilting the box, as indicated in dotted 55 lines, Figure 1, and this tilting action will free the hook and allow the cover to be removed.

On the under side of the cover, in close proximity to the suspended hook 5, I arrange a spring clip 6, adapted to receive a folded piece of paper, indicated by dotted lines 7.

When this paper, which may contain the order for the supply of milk, is placed in position, the hook is first raised to the position shown in dotted lines, Figure 1, and the paper slipped between the clip and the hook, where it will prevent the hook from falling to lowered position. The cover is then re-placed and it can be removed by the person delivering the milk. When the paper is slipped out of the clip however, the hook will fall, and when the bottles have been deposited in the container, and the cover re-placed, the hook will automatically engage the rod 2 and effectively lock the cover in position.

To one side of the container I attach a piece of metal in substantially right angled 80 form, 9, slidably held thereon by a pair of set screws 10 and this member 9 is formed with elongated slots 11 in which the screws travel, to permit adjustment.

When the device is set out by the housewife, the angled end of the member 9 is placed between the rear vertical surface of the door 12 and the door frame 13, and when the door is closed the box cannot be removed, nor can it be tilted to release the cover, so 90 that, after the milk has been deposited in the box and the cover placed thereon, there is no danger of theft for it will be necessary to first open the door before the box can be removed from its position, or the cover removed therefrom.

Provision is made, through a plurality of screw holes in the container, 13, for placing the locking member 9 on the opposite side of the box, where it is to be applied to a door 100 opening in the direction opposite that shown.

It is evident that with my device, theft of the milk bottles either from the container, or of the container itself, will be impossible.

It is also evident that modifications of the 105 construction shown may be developed with-

out departing from the spirit of the invention, and I do not therefore wish to limit myself to the exact details of construction shown and described, but:

5. What I claim and desire to secure by Letters Patent is:—

1. In a device of the character described, the combination of a box like container provided with a horizontal rod extending from one vertical wall to the opposite wall, with a cover adapted to fit snugly on the container, a loosely pivoted locking hook suspended from the under side of the cover and adapted to engage said rod when the cover 10 is placed in position on the container and capable of releasing its hold on said rod when the container is tilted from vertical position.

2. In a milk bottle container, the combination of a box member having a horizontal rod therein, and means for securely holding it between a door and a door frame, with a cover for the container, a hook loosely suspended from the under side of

the cover and in substantially vertical alignment with the rod, said hook being adapted when in full lowered position to engage the rod and to be released therefrom when the box member is tilted, and a paper clip in close proximity to the hook whereby the 25 hook will be held in inoperative position by a paper when inserted in the clip.

3. In a device of the character described, the combination of a receptacle member, a door and door frame, and a reversible and adjustable locking member secured to the receptacle capable of being held between the door and the door frame when the door is in closed position.

4. A milk bottle receptacle provided with a cross rod, and a cover for the receptacle provided with a depending hook adapted to engage said rod when the lid is placed in position, and to release its hold on the rod when the receptacle is tilted.

45 In testimony whereof I affix my signature.

HARRY H. BELLMAN.
